UNITED STATES PATENT OFFICE

EMMA KOHLMEIER, OF MANITOWOC, WISCONSIN, ASSIGNOR OF ONE-HALF TO ELMER KOHLMEIER, OF MANITOWOC, WISCONSIN

WINDOW SCREEN

Application filed December 12, 1927. Serial No. 239,463.

This invention relates to window screens.

Objects of this invention are to provide a novel form of window screen which is adapted to be placed in a window and contact with the sash, and which is so constructed that the draft through the screen may be regulated to suit any condition, such as those found in hospitals, homes, or other places, for instance.

Further objects of this invention are to provide a window screen which has sliding glass panels which may be arranged in overlapping relation, if desired, or which may be slid as required to direct the draft whenever needed, and which also may be slid outwardly to the ends of the screen to protect the curtains from dust and from damage against the screens.

An embodiment of the invention is shown in the accompanying drawings in which:

Figure 1 is a view of a window with parts broken away showing the screen in place;

Figure 2 is a sectional view on the line 2—2 of Figure 1;

Figure 3 is a sectional view on the line 3—3 of Figure 2;

Figure 4 is an enlarged sectional detail showing a modified form.

Referring to the drawings, it will be seen that the screen comprises a framework having an upper and lower member indicated by the reference characters 1 and 2, and having side members 3. A screen 4 is stretched across this framework and is secured in any suitable manner. For instance, the screen may be carried by the auxiliary strips 5 and its ends covered by the strips 6. The frame has its upper and lower members provided with slots 7 and 8 within which glass panels 9 and 10 are adapted to slide. Preferably, these glass panels are provided with handles or projections 11 cemented thereto or otherwise secured.

It is to be noted that the slots 7 and 8, as shown in Figure 2, may be for a predeter-

mined distance, so that the two panes 9 and 10 may be slid into overlapping relation at the center of the window to offer the minimum obstruction to the air.

Further, it is to be noted that the panels 50 may be slid to the ends of the screen to thus protect the curtain against damage from dust and from striking against the screen.

It will be seen further that the device may be very readily positioned within a window 55 and thereafter the sash may be slipped down to hold it in place.

It is to be noted that in place of having the slots 7 and 8 formed in the body of the screen frame, that these slots may be formed, 60 as shown in Figure 4 by a folded sheet metal guide 12. This sheet metal guide is folded so as to provide slots 7' and 8', and is attached to the body of the main frame in any suitable manner, as by means of the screws 65 13.

It will be seen that a very simple type of screen has been provided which does not have the disadvantages heretofore experienced with the usual types of screens, but 70 which instead is so constructed that the draft may be regulated and directed to one or the other side or to the center of the screen.

Although the invention has been described in considerable detail, such description is intended as illustrative rather than limiting as the invention may be variously embodied and as the scope of such invention is to be determined as claimed.

I claim:

A window screen comprising upper and lower parallel members, side members connecting said upper and lower members, said side members being formed with vertical grooves, said upper and lower members being formed with parallel longitudinal slots, the slots extending inwardly from beneath the upper and lower members to a point beyond the center thereof so that the inner ends of the slots are arranged in overlapping 80 85 90 95

relation, movable panels having their ends arranged in the slots in the upper and lower members for sliding movement whereby said panels may be arranged at various positions 5 with respect to the upper and lower members and the overlapping portion of said slots being equal to the width of each slideable panel.

10 In testimony that I claim the foregoing I have hereunto set my hand at Manitowoc, in the county of Manitowoc and State of Wisconsin.

EMMA KOHLMEIER.
